BY *Victor J. Evans*

ATTORNEY

UNITED STATES PATENT OFFICE.

NICHOLAS PSENKA, OF CANTON, OHIO.

CONVEYER TRUCK.

Application filed April 30, 1925. Serial No. 27,083.

To all whom it may concern:

Be it known that I, NICHOLAS PSENKA, a citizen of the United States, residing at Canton, in the county of Stark and State of Ohio, have invented new and useful Improvements in Conveyer Trucks, of which the following is a specification.

This invention relates to truck bodies, and more particularly to what I term a conveyer truck.

One of the main objects of the invention is to provide a truck body and means associated therewith whereby coal and other materials of a similar nature may be readily discharged from the body. A further object is to provide simple and efficient means for feeding the material from the body onto the conveyer, this means being so constructed and arranged as to effectually prevent choking or jamming of the conveyer. Further objects will appear from the detail description.

In the drawings:—

Figure 1 is a plan view of the truck body partly broken away;

Figure 2 is a section taken substantially on line 2—2 of Fig. 1;

Figure 3 is a front view of the truck body;

Figure 4 is a section taken substantially on line 4—4 of Fig. 1;

Figure 5 is a section taken substantially on line 5—5 of Fig. 4;

Figure 6 is a section taken substantially on line 6—6 of Fig. 2;

Figure 7 is a detail of the clutch member secured on the drive shaft;

Figure 8 is a detail of the connection between the conveyer cover plate and the operating lever therefor.

The truck includes a body 1 supported upon a frame 2 of any suitable or preferred construction, this body including side plates 3 and bottom plates 4 and 5 which are inclined downwardly and inwardly from the ends of the body so as to form a bottom of substantially V-shape in longitudinal section. This serves to cause material within body 1 to flow to the lower central portion thereof.

A conveyer frame 6 is supported by body frame 2 beneath the rearward bottom plate 5, this conveyer frame being disposed below and normally adjacent to plate 5. A shaft 7 is rotatably mounted in the upper portion of frame 6 transversely thereof and a shaft 8

is similarly mounted in brackets 6^a extending from the lower portion of frame 6. Shaft 8 also passes through brackets 6^b secured to sills 2^a which support the cross-beams 2^b to which frame 2 is secured. This provides 60 a hinge mounting for the lower end of the conveyer, for a purpose to be described. Sprocket-wheels 9 are secured on these shafts and receive chains 10 passed about the same, these chains being connected by flights 11 65 which, on the upper run of the conveyer, travel upon the upper face of the bottom of a trough formed by side rails 6' and plate 6^c of the conveyer structure. A bevel gear 12 is secured on shaft 8 and meshes with a 70 bevel gear 13 secured on the rearward end of a counter-shaft 14 and a sprocket-wheel 15 is secured on the forward end of this shaft and receives a chain 16 which also passes about a sprocket pinion 17 secured on a 75 clutch member 18 which extends about and is spaced from a drive-shaft 19 which may be driven in any suitable or preferred manner from the engine of an automobile truck in connection with which the body 1 is used, this shaft being usually an extension of the engine crank shaft. Clutch member 18 80 contacts with a clutch member 20 which fits about the rearward end portion of shaft 19 and is secured by cap screws 21 in a sectional clamp 22 which is tightly secured about shaft 19 for rotation therewith. When clutch member 18 is in engagement with clutch member 20 sprocket-wheel 17 is 85 rotated with shaft 19 so as to drive the elevator through the counter-shaft 14 and associated parts. As members 18 and 20 are of greater interior diameter than the diameter of shaft 19, vibration due to rotation of this shaft will not be transmitted to member 18 and associated parts. This relieves the clutch and associated parts of undesirable strains and vibration and consequent wear, which is a desirable feature in mechanism of this character.

A bracket 23 of inverted U-shape is secured to the front of body frame 2 and slidably supports a bar 24 the body portion 24^a of which is of squared cross-section. This bar is provided, at its rearward end, with a depending arm 25 having at its lower end a sectional or collar strap 26 which is secured about the neck of clutch member 18 in such manner as to permit rotation of the clutch member while ensuring movement of 100 105 110

the clutch member along shaft 19 into and out of operative position in accordance with adjustment of arm 25. An expansion spring 27 is mounted about the body 24^a of bar 24 and is confined between the inner arm of bracket 23 and a stop member such as screw 28 secured through the body of the bar adjacent the outer end thereof. This spring acts to urge the bar in such direction as to move clutch member 18 out of engagement with clutch member 20. The bar 24^a is further provided at its inner end with an upwardly projecting lug 29 with which contacts a finger 30^a provided at the lower end of a clutch control rod 30 and disposed at right angles thereto. Rod 30 is rockably mounted through the inner end portion of the top of bracket 23 and through a bracket 31 secured to body frame 2. An operating lever 32 is secured on the upper end of the rod for turning the same in proper direction for throwing the elevator into and out of operation. By turning rod 30 so as to position finger 30^a as illustrated in Fig. 4, clutch member 18 is moved into engagement with clutch member 20 thus throwing the elevator into operation. By turning rod 30 so that finger 30^a is disposed substantially at right angles to the position illustrated in Fig. 4, arm 25 is released and bar 24 is moved forwardly by spring 27 disengaging clutch member 18 from clutch member 20 and throwing the elevator out of operation. This provides simple and efficient means whereby the operation of the elevator can be readily controlled and, in practice, the lever 32 is positioned adjacent the cab of the truck so as to be readily accessible from the driver's seat.

40 To prevent clogging or choking of the elevator I provide a cover plate 33 which is mounted adjacent the underface of bottom plate 5 and operates through slots 34 provided through angle bars 34^a and plates 34^b depending therefrom, the plates being also provided with slots which are aligned with the slots of the angle bars. The angle bars 34^a are rigidly secured in frame 2 adjacent and parallel with the side rails of the conveyer frame and co-operate with plates 34^b to provide a well in which the conveyer operates. Plate 33 is slidably supported upon rods 35 provided for this purpose, or in any other suitable or preferred manner, and the plate is of such width that the lower inner corner portion thereof fits into the lower end of slot 34 when the plate is in open position, outward movement of the plate away from the conveyer being limited by the side members of the body frame 2. A bracket 36 is secured to the underface of plate 33 at the central portion of the outer edge thereof. This bracket is provided with a depending slotted lug 37 which receives the flattened upper portion 38^a of a sleeve 38, this sleeve

being pivotally secured in lug 37 by a pin 39. Sleeve 38 slidably receives the upper portion of an arm 40^a provided at the inner end of a rod 40 rockably mounted on cross-beams 2^b beneath the body frame 2, arm 40^a being disposed at right angles to the rod and rigidly secured thereto as by being formed integrally with the rod, as illustrated, or in any other suitable or preferred manner. An operating lever 41 is secured on the forward end of rod 40 and is positioned so as to be readily accessible from the driver's seat. Before loading the truck body with coal or other material which is to be discharged by means of the conveyer, the conveyer is covered by moving lever 41 in such direction as to slide cover plate 33 inwardly across the conveyer such a distance as to completely cover the same. This provides, in effect, a continuous rearward bottom plate for the truck body and prevents the coal or other material from entering into the trough of the conveyer, plate 33 extending from the lower edge of plate 5 to within a short distance of the upper edge thereof, as illustrated. When it is desired to discharge the coal from the body plate 34 is moved into open position gradually so as to permit the upper portion of the load of coal or other material to first enter the upper portion of the conveyer trough from which it is removed by means of the flights 11, the conveyer being thrown into operation before plate 34 is moved in opening direction. As will be noted from Figure 1, the inner edge 34^c of cover plate 34 is beveled upwardly and outwardly so that, as the plate is moved into open position, the opening through which the coal is admitted to the conveyer trough will gradually increase downwardly of the conveyer and the conveyer trough will not be completely uncovered until the greater portion of the load has been discharged from the trough. This effectively prevents such a quantity of coal from entering the conveyer trough as would tend to choke the conveyer or seriously interfere with its operation. By the time the conveyer cover plate is moved into full open position practically all of the coal or other material will have been discharged from the body with the exception of a small quantity which may collect in the bottom of the body at either side of the conveyer trough. This residue can be readily shoveled or scraped into the conveyer trough and discharged therefrom. To prevent any coal or other material from being discharged from the lower end of the conveyer I provide a gate 42 which is hingedly secured at 43 to the central one of the cross-beams 2^b which fits into the lower portion of the conveyer trough. This gate is provided, at its rearward end, with an upwardly projecting flange 44. The gate is raised by the flights

11 as they pass beneath the gate so that operation of the conveyer is not interfered with. This provides simple and efficient means whereby the contents of the body can 5 be readily discharged and loss of any portion of the contents through the lower end of the conveyer trough is eliminated.

In practice, a suitable chute may be connected to the upper end of the conveyer 10 trough in any suitable or preferred manner so as to direct the coal or other material discharged from the conveyer to any desired point. The inclination of the conveyer can be adjusted by means of a supporting rod 15 45 which can be inserted through any one, selectively, of two or more sets of angle brackets 46 secured to the under face of the conveyer frame, this rod being also inserted through suitable openings 47 provided 20 through the rear uprights of the frame structure, the different series of openings being positioned to support the conveyer at the desired inclination. This adjustment of the conveyer is permitted by the hinge connection 25 provided by the shaft 8 and associated parts, previously referred to.

By constructing and arranging the conveyer and the parts associated therewith in the manner illustrated and described, I 30 effect a very material saving in time in unloading trucks for carrying coal, gravel and other materials of a similar character in addition to providing means whereby this unloading can be quickly and easily effected 35 by one man and with power obtained from the engine of an automobile truck of which the body forms a part. This results in effecting a considerable saving in the cost of handling and delivering coal, gravel, and 40 materials of a similar character thus benefiting both the producer and the consumer. As will be understood, and as indicated herein, changes in construction and arrangement of parts of the invention can be resorted 45 to without departing from the field and scope of the same, and I intend to include all such variations, as fall within the scope of the appended claims, in this application in which a preferred form only of my invention 50 is disclosed.

What I claim is:—

1. In combination with a truck body including a trough and a conveyer operating in the trough for removing material therefrom, of a movable cover for the conveyer, and a gate member fitting in an end of the trough and in operative contact with the conveyer to prevent escape of material admitted to the conveyer upon removal of the 55 cover therefrom and having an upturned 60

portion disposed beneath a wall of the body opposite the trough.

2. In combination with a truck body including a trough, of a conveyer operable in the trough for removing material therefrom, and a cover for said conveyer having an oblique edge portion movable transversely of the conveyer. 65

3. In combination with a truck body having a bottom wall of approximately V-shape 70 in longitudinal section, a trough mounted beneath and closely adjacent one portion of said bottom wall, a conveyer operating in the trough and including flights disposed to remove material from the trough, a cover 75 plate slidably mounted adjacent the bottom wall of the body and movable across the trough for covering the same, the inner edge of said plate being inclined downwardly and inwardly toward the trough, means for 80 moving said plate into and out of operative position, and means for operating the conveyer.

4. In combination with a truck body having a bottom wall of approximately V-shape 85 in longitudinal section, a trough mounted beneath and adjacent one inclined portion of said bottom wall, said trough being adjustable to vary its inclination, a conveyer operating in the trough and including flights disposed to elevate and discharge material from the trough, a closure plate slidably mounted beneath the body and movable into position to cover the trough, means for moving said plate into and out of operative position, and 90 means for operating the conveyer.

5. In combination with a truck body including a trough, of a conveyer operable in the trough for removing material therefrom, and a cover movable transversely of the conveyer and having a tapered edge adapted 100 when the cover is moved transversely of the conveyer to gradually enlarge an opening for admission of material to the trough to be removed by the conveyer. 105

6. In combination with a truck body including a bottom wall of approximately V-shape in longitudinal section, a trough mounted beneath and adjacent one inclined portion of the bottom wall, means for optionally covering and uncovering said trough, means for elevating material in the trough and discharging it therefrom, and a gate member hingedly mounted adjacent the other inclined portion of the bottom wall of 110 the body and fitting into the lower end of the trough so as to prevent escape of material from the lower end of the conveyer. 115

In testimony whereof I affix my signature.

NICHOLAS PSENKA.
